METHOD AND APPARATUS FOR HEATING

Lee Wilson, Cleveland, Ohio

Application June 13, 1936, Serial No. 85,091

9 Claims. (Cl. 263—14)

This invention relates to a method and apparatus for heating and, in particular, to the heating of molten material disposed in a container. While the invention will be described with reference to a galvanizing pot, it has other applications as well.

Galvanizing pots, as heretofore constructed, have usually been heated from below by an open flame, although the heat loss which must be made up by the heating flame occurs at the surface of the bath, by convection and the passage therethrough of the material being coated, which is normally at room temperature. It has thus been necessary to heat the bottom of the pot to a temperature much higher than is required at the surface of the bath, to ensure that the desired operating temperature be obtained at the surface. This problem has been aggravated by the fact that the dross which forms on the surface of the bath sinks to the bottom of the pot and forms a layer having relatively low thermal conductivity. Overheating of any portion of the galvanizing pot is a very serious matter because of the fact that corrosion of the walls of the pot (if the latter are of steel, as is usual) proceeds very rapidly at temperatures above 875° F., the corrosion rate increasing at higher temperatures. Such corrosion, of course, materially shortens the life of the galvanizing pot and involves considerable expense for replacement.

I have invented a method and apparatus for heating which is particularly adapted for galvanizing pots although it has other uses as well. My invention overcomes the aforementioned objections to the previous practice in the construction and operation of such devices and is characterized by additional advantages and features of novelty which will be described in detail and particularly pointed out in the appended claims. In accordance with my invention, I mount a plurality of heat exchange tubes at spaced points about a container for material adapted to be heated, such as a galvanizing pot. The tubes are disposed substantially vertically and closely adjacent the walls of the pot. By means of burners mounted in the upper ends of the tubes I supply hot fluids to the tubes whereby they are heated to radiant condition and radiate heat to the walls of the container. The fluids are taken off from the lower ends of the tubes by an exhaust duct.

A more complete understanding of the invention may be obtained from a consideration of the following detailed description, referring to the accompanying drawings for illustration.

In the drawings, representing a present preferred embodiment of the apparatus:

Figure 1 is a view partly in plan and partly in section, on an intermediate horizontal plane;

Figure 2 is a view partly in side elevation and partly in section, along line II of Figure 1 with parts omitted; and

Figure 3 is a view partly in end elevation and partly in transverse section, along the line III—III of Figure 1; the plane on which the sectional part of Figure 1 is taken is indicated by line I—I of Figure 3.

Referring in detail to the drawings, a receptacle for material to be heated is indicated at 10. In the illustrated embodiment, this is a galvanizing pot through which sheet material is adapted to be passed for the purpose of coating. The pot has side walls and a bottom, and rests on a foundation 11 of any suitable type. A refractory wall 12 is built up around the pot and rests on a footing 13. The wall is provided with a refractory layer 14 removably supported on the top thereof. The wall is built up of refractory bricks within a casing formed by structural members 15 embedded in the foundation 11, and plates 16.

Spaced slots 17 are formed in the walls 12 at the sides of the pot 10, adjacent the upper edge thereof. Elbows 18 having caps 19 extend through the holes 17, the caps 19 being bolted to plates 20 attached to the plates 16. Tubes 21 extend downwardly from the lower ends of the elbows 18, forming continuations thereof, to a level slightly above the top of the footing 13.

An exhaust duct 22 is formed in the footing 13 and is provided with a cover 23 through which extend flanged sleeves 24. The upper ends of the sleeves 24 extend within the lower ends of the tubes 21 and sealing material 25 such as sand disposed on the cover plate 23 seals the joints between the tubes and sleeves. The ducts 22 communicate with flues 26 positioned between the walls 12 and the pot 10 adjacent the ends of the latter.

Each elbow 18 is provided with a burner 27. Each burner has a spark gap 28 for igniting it, the electrodes forming the spark gap being mounted on the burners as shown, and connected to a transformer 29 carried on a suitable frame 30, by a cable 28a.

Fuel is supplied to alternate burners 27 on each side from a header 31. The remaining burners are similarly supplied with fuel from a header 32. Individual control valves 33 are provided for each burner in the connections 34 extending thereto from the headers 31 and 32.

Fuel for combustion is obtained from a supply main 35 whence it flows through branch connections 36 to the inlet of inspirators 37 and 38. The outlets of the inspirators 37 and 38 are connected, respectively, to mixing pipes 39 and 40. The fuel input to the inspirators may be controlled by valves 41 and the function of the inspirators, of course, is to bleed a small amount of atmospheric air into the fuel, such as gas, passing therethrough. Additional air is supplied to the pipes 39 and 40 from an air main 42 and branch connections 43. The connections from the branches 43 to the mixing pipes are shown at 44 and 45. The connections from the mixing pipes 15 to the headers 31 and 32 are indicated at 46. By means of the connections described, a combustible mixture of air and gas is delivered to the burners 27 for combustion in the elbows 18 and the tube 21. The combustion products after passing through the tubes 21 enter the exhaust ducts 22 and are finally discharged from the upper ends of the flues 26.

The tubes 21 are heated to radiant condition by the passage of hot combustion gases therethrough, 25 and heat the side walls of the pot 10 by radiation and convection. By reason of the location of the burners adjacent the upper edge of the pot 10, the maximum amount of heat is liberated adjacent the surface of the material, such as spelter, in the pot, the level of which might be indicated by the dotted line 47. By the time the combustion gases reach the lower ends of the tubes 21, they have cooled somewhat and so liberate a small amount of heat to the lower strata of the material 30 in the pot. Baffles 48 are disposed in the tubes 21, in accordance with the invention described and claimed in the copending application of Wilson et al., Serial No. 49,078, filed November 9, 1935. These baffles increase the amount of heat delivered by the combustion gases to the tubes.

The ends of the burners 21 are bent downwardly. A hot spot appears on the tube wall where the gases from the burner impinge thereon, and by varying the angularity of the burner tip, the location of the area of maximum temperature on the tube wall may be so controlled as to supply the greatest amount of heat to precisely the desired point. The refractory layer 14 being removable with its top plate, permits change of radiant 45 tubes without removing the pot and even while it is hot. Conversely, the pot may be removed without disturbing the radiant tubes.

The provision of duplicate supply headers for alternate burners affords a nice control of the 55 amount of heat delivered to the space along the side walls of the pot. During periods of low production or shut down, alternate burners may be extinguished. The material in the pot, such as spelter, may thus be heated to the proper temperature without danger of local overheating of any portion of the pot itself. Since the heat is delivered to the side walls of the pot, the dross accumulating in the bottom thereof does not interfere with the transmission of heat to the material in the pot. The maximum amount of heat is delivered to the spelter adjacent the surface of the bath where the maximum heat losses occur, i. e., by convection and passage of the relatively 60 cold sheet material therethrough. By avoiding local overheating of the pot, corrosion of the walls thereof is reduced and a longer life assured, reducing the cost of pot replacements.

Although I have illustrated and described but 75 one preferred form of the invention, it will be ap-

parent that numerous changes in the construction disclosed and the method practiced thereby may be made without departing from the spirit of the invention and the scope of the appended claims.

I claim:

1. A method of heating a vessel adapted to contain molten material, including the steps of generating hot combustion gases in the neighborhood of the rim of said vessel and conducting them through conduits extending downwardly therefrom and exteriorly of the walls of the vessel.

2. Apparatus for heating a container comprising a plurality of radiant tubes disposed side by side 15 adjacent a wall of the container, a header connected to burners in alternate tubes, a second header connected to burners in the remaining tubes, and means for supplying fuel to said headers.

3. The apparatus defined by claim 2 characterized by the tubes whose burners are connected to one header being interspersed between the tubes whose burners are connected to the other header.

4. The combination with a galvanizing pot or the like open at the top, adapted to contain molten spelter and dimensioned to receive elongated sheets for coating therewith by immersion, of a plurality of substantially vertical heat exchange 30 tubes disposed along the side walls of the pot, extending substantially up to the level of said spelter, and in heat-radiating relation thereto, of means for causing a flow of hot fluid into the upper ends of said tubes and downwardly there- 35 through whereby to heat the tubes to radiant condition and thereby radiate heat to said vessel and to said spelter adjacent its surface.

5. The combination defined by claim 4 characterized by said means comprising burners disposed to deliver hot combustion gases to the open ends of said tubes for passage downwardly therethrough.

6. The apparatus defined by claim 4 characterized by said tubes being suspended from a point 45 adjacent their upper ends leaving their lower ends freely floating.

7. The combination with a galvanizing pot or the like, adapted to receive elongated sheets for immersion coating in molten spelter contained therein, of substantially vertical heat exchange 50 tubes extending downwardly along the side walls of the pot and exteriorly thereof from a level adjacent the rim of said pot, burners extending into the upper ends of said tubes, and a duct for conveying combustion gases from the lower ends of said tubes.

8. Heating apparatus comprising a galvanizing pot adapted to receive sheets for coating, a refractory wall extending therearound, and radiant 60 tubes extending downwardly between the wall and pot, said tubes being supported solely from their upper ends whereby they are vertically removable.

9. Heating apparatus comprising a galvanizing 65 pot adapted to receive sheets for coating, a refractory wall extending therearound, radiant tubes extending downwardly between the wall and container, and burners mounted in the upper 70 ends of said tubes, said pot being vertically removable from within said wall, independently of said tubes.
